STRINGED MUSICAL INSTRUMENT

Walter J. Pelensky, 19C Manheim Gardens,
Philadelphia, Pa. 19144

Filed Dec. 15, 1969, Ser. No. 20,503

Term of patent 14 years

Int. Cl. D17—03

U.S. Cl. D56—1

Fig. 2

Fig. 1

Fig. 4

Fig. 3

FIG. 1 is a perspective view of a stringed musical instrument, specifically a plucked Ukrainian kobza of the Tambur (tanbur) class, showing my new design;

FIG. 2 is a fragmentary perspective view showing the peghead from a different direction;

FIG. 3 is a face view; and

FIG. 4 is a left side elevational view thereof.

Portions of the drawings are shaded to indicate contrast.

I claim:

The ornamental design for a stringed musical instrument, as shown and described.
